TUBULAR ANCHORAGE BOOT FOR
STRUCTURAL COLUMNS

Herbert H. Moss, Brooklyn, N. Y., assignor to
The Linde Air Products Company, a corpora-
tion of Ohio

Application November 14, 1929, Serial No. 407,244

8 Claims. (Cl. 72—72)

My invention relates to anchorage boots for structural columns and more particularly to a boot comprising tubular members welded to the foot of the column for receiving anchor bolts.

5 The foot of a structural column is usually provided with some form of an anchorage boot to which members, such as anchor bolts, are secured to hold the column in an upright position on its foundation.

10 Anchorage boots heretofore have comprised an arrangement of structural steel shapes, such as angles, tees, and channels, and one or more steel plates; and these steel shapes have been either riveted or welded to each other and to the foot 15 of the column. Boots of this character are objectionable because they require a number of parts, and must be accordingly laid out, cut, and fitted to each other and to the column. Further, in the riveted construction a considerable 20 amount of labor is required for accurately locating and punching the rivet holes; while in the welded construction the amount of welding required is relatively high. Boots of this character also are objectionable because they are 25 easily damaged in transit and in erection.

According to my invention, the foregoing and other objections are avoided by providing a one piece tubular boot member for each anchor bolt which is welded to a side of the foot of the column. Where a flanged column is used, the member is preferably welded to the edge of the flange.

As a result of reducing the number of parts, and due to the simplified construction of my 35 boot, an economical and strong boot is obtained per unit of weight.

One of the objects of my invention therefore, is to provide a structural column with an anchorage boot rigidly secured to it.

40 Another object of my invention is to construct an anchorage boot that will provide a positive means for securing the column to the foundations which have been designed on the assumption of fixed end conditions.

45 Another object of my invention is to construct an anchorage boot by means of welding wherein the application of welding thereto is facilitated by the design thereof to obtain thorough penetration of the weld metal, into the base metal about the joint formed by my design.

50 Another object of my invention is to construct an anchorage boot comprising a plurality of tubular members welded to the foot of the column parallel to its longitudinal axis and at the

greatest distance from the common geometrical center of the cross section of the column.

5 Another object of my invention is to weld an anchorage boot to the foot of a column so that the forces tending to overturn the column will be transmitted to the anchorage bolts along a line substantially parallel and adjacent to the line of weld metal joining the boot and the column.

10 Another object of my invention is to construct an anchorage boot that can be successfully applied to a column in the field.

15 These and other objects of the invention will be more fully understood from the following description of my invention disclosed in the accompanying drawing in which,

Fig. I is an elevational view of the foot of a column with a boot attached to the column and secured to a foundation;

Fig. II is a cross section of the boot and the 20 column on line II—II of Fig. I;

Fig. III is an elevational view of a boot welded at the top and bottom to the foot of a column and also disclosing a clamp for holding the tubular members in place while they are being 25 welded;

Fig. IV is an end view of the boot and clamp shown in Fig. III;

Figs. V to VII are enlarged sections of different forms of boot members.

30 Various forms of structural columns may be provided with anchorage boots of my invention. For the purpose of illustrating my invention, a flanged column 1 is shown having a boot 2 attached thereto comprising a tubular member 3 welded to each flange 4 of the column along its edge 5. The lower ends of the tubular members 3 are set back from the base end of the column to prevent it from contacting with the base plate 6 upon which the foot of the column rests.

35 The tubular members 3 are secured to the foundation by means of rods anchored in the foundation and secured to the members. The anchoring means herein shown comprise anchor bolts 7 anchored in a foundation 8 and extending upwardly through the metal plate 6 and the tubular boot members 3. A washer 9 fits over the end of each bolt 7 and is pressed against the top of the tubular member by a nut 10 cooperating with the threads on the end 40 of each anchor bolt.

45 In Fig. I the tubular members 3 are welded throughout their length to the column flanges. Sometimes in such a long seam of weld metal, stresses are set up in the metal due to the 50

55

contraction of the metal upon cooling. To reduce or avoid these stresses and also to decrease the cost of welding, the tubular members may be welded to the flanges 4 at the top 5 and bottom of the tubular boot members 3 leaving a gap between the seams of weld metal 11 at the middle of the members as is shown in Fig. III.

To facilitate the welding of the boot members 3 to the flanges 4 of the structural column 1, one or more clamps 12 may be used to hold the boot members in place while they are welded to the edges of the flanges 4. The clamp shown in Figs. III and IV comprise two 15 U shaped members 13 provided with sockets 14 in each of the inside corners to receive the boot members. The end of the U members are coupled together by bolts 16 passing through the flanges 17 on the ends of the members 13. 20 The clamp 12 is slipped over the end of the column 1 and the boot members 3 are inserted in the sockets 14 and clamped against the column flanges 4 by tightening the nuts on the bolts 17.

25 Where thick-walled pipe is used for the boot members, a groove 18 may be milled in the outer surface of the pipe, lengthwise thereof, to receive the edge of the flange 4 of the column, as shown in Fig. V. The groove 18 insures 30 the proper alignment of the pipe with the edge of the flange 4 while the weld metal 11 is deposited on each side of the flange.

The tubular boot members 3 may also be made of cast metal, preferably cast steel, in 35 which the groove 18 of the proper dimensions to fit the edge of the column flange 4 is cast in the member. A member 3 of this form is shown in Fig. VI welded to the flange 4 of a column by the weld metal 11 deposited on each 40 side of the flange.

45 Another modification of a boot member is shown in Fig. VII in which the boot member 3 is made of sheet metal bent in a tubular form over a mandrel leaving an open side in the member provided with flanges 19 which are welded to each side of the flanges 4 on the column.

50 While I have shown the preferred forms of my invention, changes in the details shown may be made without departing from the scope of

my invention as defined in the appended claims. I claim as my invention:

1. In combination, a structural steel shape having a flange, and a metal tube having its axis parallel to said flange and its wall welded to 5 said flange.

2. In combination, a structural steel shape having flanges, and metal tubes having their axes parallel to said flanges, one tube being welded to each flange. 10

3. In combination, a structural steel shape having parallel flanges, and metal tubes having their axes parallel to said flanges, each flange having a tube welded thereto near one end of the flange. 15

4. In combination, a structural steel column having parallel vertical flanges, and metal tubes having their axes parallel to said flanges and severally welded to the flanges adjacent the foot 20 of the column.

5. In combination, a structural steel column having parallel vertical flanges, said flanges having their outer edges located at the maximum distance on the column from the center of gravity of the cross-section of said column, and metal tubes having their axes parallel to said edges and severally welded thereto. 25

6. An anchorage boot for a column comprising a tubular member extending in a lengthwise direction for a substantial distance along said column and disposed adjacent the foot thereof; and longitudinal lines of weld metal extending between said member and said column to 30 secure the member to said column.

7. An anchorage boot for a flanged column 35 comprising at least one metal tube welded to the edge of a flange of the column in a lengthwise direction thereof, said tube having the bore thereof spaced from the edge of said flange by a distance comprising substantially the thickness of the wall of said tube and any interposed weld metal. 40

8. An anchorage boot for a column having a plurality of flanges, said boot comprising a plurality of tubular members each having a groove 45 therein for receiving an edge of one of said flanges; and longitudinal lines of weld metal deposited along the line of contact between the edges of said grooves and said flanges.
